UNITED STATES PATENT OFFICE.

FREDERICK J. KIESER, OF CHICAGO, ILLINOIS.

TOBACCO-PIPE.

1,065,372.

Specification of Letters Patent. Patented June 24, 1913.

Application filed November 10, 1911. Serial No. 659,478.

To all whom it may concern:

Be it known that I, FREDERICK J. KIESER, a citizen of the United States, residing in the city of Chicago, county of Cook, and 5 State of Illinois, have invented certain new and useful Improvements in Tobacco-Pipes, of which the following is a specification.

The object of this invention is to provide a pipe which will accommodate, in proportion to its size, a very large amount of tobacco, so as to do away with frequent refilling; which will make it unnecessary to use the finger or an outside appliance to compress the contents of the bowl, after the 10 pipe is lighted, in order to keep it burning properly; and which will do away with the drawing of the smoke through the whole mass of the unburned tobacco in the pipe.

In the drawings Figure 1. is a sectional side elevation of my pipe, showing the false bottom of the tobacco chamber in depressed position, and showing, in dotted outlines, the upper portion of the bowl in raised position; Fig. 2. is a vertical section through 25 the lower portion of the tobacco chamber and connected parts, with the false bottom of the chamber in raised position; and Fig. 3. is a top plan view of the bowl.

Referring to the drawings, an ornamental outer bowl 6 is fastened, by screws 7, metallic casing 8, consisting of bottom 9, inner vertical cylinder 10 and outer vertical cylinder 11, said cylinders being separated by cylindrical well 12. To outer cylinder 11 is 30 connected, on the outside, boss 13 which is formed with vertical tubular opening 14, and also with stemhole 15, the lower end of which communicates through smoke channel 16 with opening 14. This opening 14 widens 35 at its lower end into chamber 17 which is closed by screwplug 18. On cylinder 10 there is mounted between it and cylinder 11, with an easy sliding fit, cylinder 19, the upper portion of which is enlarged and fitted 40 on the inside with an insulating ring 20 of noncombustible material, such as fireclay. The lower edge of cylinder 19 is provided with outer annular flange 61, adapted to engage a stop ring 62 which is threaded into 45 the upper end of cylinder 11. Immediately below ring 20, cylinder 19 is provided in its

wall with circular smoke channel 21, communicating with the interior of cylinder 19 by apertures 22. Immediately below ring 20 there is threaded into a suitable boss 23, attached to cylinder 19, tube 24 which fits with an easy sliding fit into opening 14, extending downward therein as far as cylinder 19 extends downward into well 12, and the interior of which communicates at its upper 55 end, through channel 25, with channel 21, while the lower end opens into opening 14, and through it communicates with channel 16. In order that the communication with channel 16 be not interrupted even when tube 24 is in its lowest position, opening 14 is enlarged by vertical groove 26 which extends from channel 16 to chamber 17. Gland 27 and packing 28 are provided to secure 60 airtight connection between tube 24 and the upper end of opening 14. Into stemhole 15 is threaded hollow stem 29, provided with mouthpiece 30. In cylinder 10 is slidably mounted false bottom 31, provided with outer depending flange 32, and inner depending 65 flange 33, which latter surrounds opening 34 in the center of false bottom 31, and corresponds to annular boss 35 which projects upward from bottom 9, surrounding opening 65 in the center thereof. On flange 33 70 and boss 35 are mounted the smaller ends of spiral springs 36 and 37 respectively, the larger ends of which bear against a plate 38, provided with flange 39 which extends upward and downward from its outer 75 edge. Through openings 34 and 65, and through corresponding openings 40 and 41 in the center of plate 38 and in the center of the bottom of outer bowl 6, respectively, extends vertical stem 42, provided at its upper 80 end with horizontal pin 43, adapted to engage with its ends the upper edge of false bottom 31, and provided at its lower end with knob 44, adapted to be engaged by the fingers of the operator. Annular groove 45 85 is provided, slightly above knob 44, in stem 42, for engagement by catch 46, for the purpose of holding the stem 42 in elevated position. Another spring catch 47 is provided for the purpose of holding false bottom 31 in the position shown in Fig. 1. when 90 desired. The top of cylinder 19 is closed 95

by cover 48 which is oscillatably held by vertical pivot 49, and also hinged on horizontal rivet 50, so as to be capable both of being swung sidewise around pivot 49, and 5 tipped upward, with rivet 50 as a fulcrum. Catch 51 is provided to lock cover 48 in position. A shutter 52 is attached to the underside of cover 49 by means of stem 53, to the upper end of which is attached knob 54 10 as a handle for the turning of shutter 52, so as to either bring airholes 55 in shutter 52 into register with corresponding airholes 56 in cover 49, or to shut off ventilation, as desired. There is also attached to shutter 15 52 a vertical deflecting wing 57, extending from the center of the space under shutter 52, with an upward slant of its lower edge, toward the circumference of shutter 52.

The operation of my device is as follows:—Catch 46 is disengaged from groove 45, and stem 42 pulled downward, by means 20 of knob 44, bringing down with it false bottom 31, and compressing springs 36 and 37 until spring catch 47 engages the upper edge 25 of false bottom 31, locking it in the position shown in Fig. 1. Stem 42 is thereupon pushed upward again until catch 46 again engages groove 45, thereby locking stem 42 in the position shown in Fig. 1. Cylinder 30 30 19 is then pulled upward until flange 61 engages stopring 62; cover 48 is opened, and the whole space between false bottom 31 and cover 48 filled with tobacco, which is firmly pressed down and then lighted in the 35 usual way, whereupon cover 48 is closed with shutter 52 in such position as to give the desired ventilation. As the tobacco burns down, cylinder 19 is pushed down from time to time, thereby pushing fresh tobacco from 40 below into the fire chamber surrounded by ring 20, and packing the burning tobacco therein into close contact with such fresh tobacco. After cylinder 19 reaches its lowest position, the same purpose is accomplished 45 by releasing catch 47, and thereby causing springs 36 and 37 to push the tobacco in cylinder 10 upward until all of it has reached the space surrounded by ring 20, where it is consumed by the fire therein. 50 Further upward movement of false bottom 31 is prevented by its engagement with pin 43. In order to prevent an accumulation of unburned tobacco under the center of cover 48 (the air suction being mainly around the 55 circumference, through the location of apertures 22) wing 57 is occasionally rotated by means of knob 54, thereby pushing the tobacco from the center toward the outside. Chamber 17 serves for the accumulation, and 60 the opening closed by screwplug 17 for the removal, of condensation moisture, etc. Ashes are from time to time removed by the opening of cover 48.

It is manifest that stem 42, with accessories, may be omitted, inasmuch as false bottom 31 may be pushed down into the position shown in Fig. 1, by the finger of the operator inserted from above; while its upward movement can easily be limited by pins projected from the inner side of cylinder 10, just below its upper edge; also that false bottom 31 and springs 36 and 37 may be employed independent of the use of the two part telescoping bowl.

I claim:—

1. In tobacco-pipes the combination of a bowl having a firechamber at its upper end, and a smoke exhaust from the circumference of the firechamber, with a cover, and a vertical rotatable stem penetrating the center 80 of the cover, provided at its upper end with a knob, and at its lower end with an eccentric wing, substantially as and for the purpose described.

2. In tobacco-pipes, the combination of a 85 bowl with a false bottom; springs interposed between such false bottom and the real bottom of the bowl; a vertical stem slidably mounted in the center of said bottoms and provided with a projection adapted to 90 engage the upper face of the false bottom; means to lock said stem in raised position; and means to lock said false bottom in lowered position; substantially as and for the purpose described.

3. In tobacco-pipes, the combination of a bowl having a firechamber at its upper end, a smoke exhaust from the circumference of such firechamber, and a false bottom; with spiral compression springs interposed between such false bottom and the real bottom of the bowl; a flanged disk interposed between said springs; a vertical stem slidably mounted in the center of said bottoms and disk, and provided with a projection to engage the upper face of the false bottom; means to lock said stem in raised position; and means to lock said false bottom in lowered position; substantially as and for the purpose described.

4. In tobacco-pipes, the combination of a bowl comprising two telescoping portions with a firechamber located in the upper end of the upper portion of the bowl; a smoke exhaust from the circumference of the fire 115 chamber; a false bottom in the lower portion of the bowl; springs interposed between such false bottom and the real bottom of the bowl; a vertical stem slidably mounted in the center of said bottoms and provided with 120 a projection to engage the upper face of the false bottom; means to lock said stem in raised position; and means to lock said false bottom in lowered position; substantially as and for the purpose described.

5. In tobacco-pipes, the combination of a

bowl comprising two telescoping portions with a firechamber located in the upper end of the upper portion of the bowl; a smoke exhaust located immediately below the fire-chamber; a telescoping pipe leading from the smoke exhaust to a telescoping chamber attached to the lower portion of the bowl;

and a stem having an opening connecting with the lower end of the telescoping chamber.
